AUTOPILOT

Lee J. Vetter, Overland Park, Kans., assignor to King
Radio Corporation, a corporation of Kansas

Filed June 26, 1969, Ser. No. 17,900

Term of patent 14 years

Int. Cl. D10—99

U.S. Cl. D52—6

Fig. 1.

Fig. 2.

FIG. 1 is a front view of an autopilot showing my new design; and

FIG. 2 is a perspective view of my autopilot.

The undisclosed side of the instrument is substantially the same in appearance as the side shown, the rear is plain.

The conventional letters disclosed in broken lines are shown for illustrative purposes only.

I claim:

The ornamental design for an autopilot, as shown and described.
